CLOSURE FOR BOTTLES OR THE LIKE

Benjamin H. Anibal, Bloomfield Hills, Mich.

Application August 28, 1933, Serial No. 687,115

8 Claims. (Cl. 215—98)

The invention relates generally to locks and it has particular relation to a lock for bottle caps or the like.

One object of the invention is to provide an improved bottle cap which may be so locked on a bottle that unauthorized persons normally will not be able to remove the cap and hence the contents of the bottle without breaking the latter.

Another object of the invention is to provide a bottle cap of this character which includes a simple form of combination lock that may be readily manipulated either to lock the cap on the bottle or to permit its removal by one possessing the combination.

Another object of the invention is to provide a bottle cap of locking character which may be manufactured in a very efficient and economical manner so as to provide a cap not prohibitive in use because of its cost.

For a better understanding of the invention reference may be had to the drawing illustrating one form thereof, wherein:

Figure 1 is a fragmentary and elevational view of a bottle illustrating a cap constructed according to one form of the invention, with the cap shown in vertical cross section.

Fig. 2 is a fragmentary view as seen from the right side of Fig. 1, with parts of the cap in cross section so as to illustrate certain details more clearly.

Fig. 3 is a cross-sectional view taken substantially along the line 3—3 of Fig. 1.

Referring to Fig. 1, an ordinary bottle is indicated at 10 and is provided with a neck 11 having conventional threads 12. The bottle cap illustrated comprises an inner shell 13 having grooves 14 in its inner peripheral surface for receiving the threads 12 on the bottle neck, and an end wall 15 for closing the opening in the bottle. Normally, a layer 16 of sealing material may be disposed between the end wall 15 and the end of the bottle neck, if a more perfect seal is desired. The outer periphery of the shell 13 is slightly tapered, as indicated at 17, and at the upper and lower ends of the taper, shoulder portions 18 and 19 may be provided for a purpose which will later be set forth. The tapered portion of the shell also is provided with an annular groove 20 and the purpose of this groove will also be set forth hereinafter. At its upper side, the end wall 15 of the shell is provided with a pair of radially spaced and circumferentially extending ribs 22 and 23 and, as best shown by Figs. 2 and 3, these ribs are not completely annular but are separated at one

point to provide a substantial space 24. At either side of this space, the ribs are bridged by walls 25 and 26 respectively. A single and wide rib might be used in place of two ribs, but by using two ribs, the cost of the cap may be reduced.

The cap also includes an outer shell 28 telescopically fitting over the inner shell 13, which is provided with inner shoulder portions 29 and 30 adjacent the shoulders 18 and 19 on the inner shell, and an inner tapered portion 31 adjacent the tapered portion 17 on the inner shell. These parts of the shells are substantially complementary so as to properly position the outer shell on the inner shell and provide a more closely united and stronger assembly. This is desirable particularly in properly guiding the outer shell in any rotary movement thereof on and relative to the inner shell and in providing a more rigid assembly when the shells are locked together for simultaneous rotary movement.

The shells are retained in assembled relation by means of a split locking ring 32 which is partially disposed in the groove 20 in the inner shell, and in a groove 33 in the outer shell. This ring is of such construction that it naturally tends to contract into the groove 20 but the groove 33 is of such dimensions that the ring may expand thereto sufficiently to permit inserting the inner shell into the outer shell. The side wall of the outer shell extends substantially above the end wall 15 of the inner shell when the parts are in assembled relation, and is provided with diametrically disposed openings 34 and 35. Upwardly of these openings, the outer shell has an end wall 36 which closes it similarly to the closing of the inner shell by the end wall 15. Thus within the upwardly projecting portion of the side wall on the outer shell and between the end walls 15 and 36, a substantial space is provided which is adapted to receive a locking device to be hereinafter described.

As shown best by Figs. 2 and 3, the upper part of the upper shell has spaced projections 40, 41 and 42 at each side of the diametrical line of openings 34 and 35, which define transverse spaces 43 and 44 extending substantially to the rim of the shell. The projections 40 are bridged by an upper portion 45 integral with the shell, as shown by Fig. 1, but between the pairs of projections 41 and 42, a space 46 is provided as shown by Fig. 2 which is open substantially to the upper and base portion 36 of the shell.

A locking device provided in the space in the outer shell above the end wall 15, includes a transversely extending pin 47 having a conical

head 48 at one end and it will be noted that this head has circumferentially spaced and scribed indicia. A sleeve 49 having similar indicia is rotatably mounted on the right end of the pin 47 and substantially abuts the head 48, and this sleeve at its left end terminates in a cam 50 which, as best shown by Fig. 2, has radially and oppositely projecting portions 51 and 52. A second sleeve 53 has a press fit on the left end of the pin for rotation therewith and for additionally locking the sleeve to the pin, a portion of the sleeve as indicated at 54 may be pressed into a groove in the pin. Manifestly, other suitable means may be used for locking the sleeve 53 to the pin so that they will rotate together. The sleeve 53 is provided with a cam 55 which may be identical to the cam 50 and on adjacent sides of the cams, the sleeves are provided with short and substantially abutting portions. It follows that the cams are disposed in spaced relation and that they can not move axially relative to the pin. The cams are so shaped that when in proper vertical positions as shown by Figs. 1 and 2, and with the space 24 directly below the space 25 between projections 42, the cams and pin may be moved transversely so as to dispose the cam 50 between the pair of projections 42 and between the end walls 25 and 26 on the inner shell. When the cam 50 is so positioned, it locks the shells so that upon turning the outer shell, the inner shell turns therewith. With the cams and pin in positions as shown in Fig. 1, the outer shell may turn relative to the inner shell and by turning the pin 47 and/or loose sleeve 53, one or both cams may be so positioned that the pin and cam assembly cannot be moved to the right because one cam would engage one of the ribs 41 and 42 as the case may be. The wall 45 of course will prevent any undesirable movement of the assembly in the opposite direction.

It will be appreciated that it is necessary for both cams to be positioned vertically as shown and that the pin 47 and sleeve 49 be separately turned to properly position the cams to permit transverse movement of the assembly to lock the shells. It will also be appreciated that the arrangement is of such character that normally no one would be able to see from the outside how the cams were positioned and it would be necessary to have predetermined knowledge as to how the pin and sleeve 53 should be turned. By numbering the indicia on the sleeve 49 and on the head 48 and providing a suitable marker on the outer shell 28 adjacent thereto as shown by Fig. 3, and with a predetermined knowledge as to where the indicia on the sleeve 49 and head 48 should be with respect to the marker on the shell, one may readily position the cams 50 and 55 to enable their transverse movement into locking positions. In actual practice, it will probably be easier to turn sleeve 49 until the combination indicia thereof is aligned with the marker on the shell, and then turn pin 47 until the combination indicia thereof is aligned with that on the sleeve and hence with the marker on the shell.

In manufacturing the sleeve 49, the indicia thereon may be formed by pushing the outer end of the sleeve into a tubular die member having circumferentially spaced and axially directed teeth for forming or scribing lines thereon and it is apparent that in the manufacture of numerous sleeves without making observations as to the position of the sleeve with respect to the tubular die, the indicia may be positioned automatically with respect to the cam in a varying

number of ways so that in effect each sleeve manufactured would have its lines scribed differently, and this automatically would provide a different combination lock on each cap manufactured. Furthermore, in fastening the pin 47 to the sleeve 53, by not directing any attention to their relative turned positions, the combination may be varied automatically so as to avoid duplicates.

The construction described may be manufactured from metal or other suitable material and the parts, with possibly the exception of the pin 48, may be manufactured by a die casting process. After manufacturing the parts, the sleeves 49 and 53 may be disposed in the positions shown before assembling them with the pin, by tilting each sleeve and inserting it through the adjacent opening in the side wall of the outer shell 28, and then the pin 47 may be pushed through the sleeve 49 and then through the sleeve 53. As stated previously, the sleeve 53 will have a press fit on the pin so as to cause its rotation therewith and after the parts are assembled, metal in the end of the sleeve may be pressed into the groove in the pin. Then prior to assembly of the inner and outer shells, the cams may be turned until they are properly positioned for movement between the projections 41 and 42, and then the position of the indicia on the outer end of sleeve 49 and on the head 48 of the pin may be noted with respect to the marker on the outer shell. After noting such positions of the indicia with respect to the marker on the outer shell 28, the inner shell 13 may be moved into the outer shell and this causes expansion of the locking ring 32 into the groove 33, until grooves 20 and 33 become aligned, whereupon the locking ring contracts into groove 20 to hold the shells in assembled relation. As the parts are now assembled they are locked positively against separation and it is impossible for anyone to learn of the combination except by a tedious hit-and-miss process which would be practically impossible in view of the enormous number of combinations that would be possible. When the parts are so assembled, and with the cams 50 and 55 aligned with the spaces 43 and 44, the cams may turn and the ribs 22 and 23 are so designed that they will not interfere with this rotary movement. This automatically locks the pin against transverse movement and hence causes the outer shell to become rotary with respect to the inner shell. When the cams are positioned for locking the shells, they may be moved to the right so as to lock the shells together and then the cap may be mounted on the bottle. It of course will be necessary to move the cam 50 between the end walls 25 and 26 of the inner shell and, in order to properly position the inner and outer shells to facilitate this movement, markers at the bottom edges of the shells may be provided so as to indicate when the space between the end walls 25 and 26 is in alignment with the pin and at the proper side of cam 50.

The cap provides a capable combination lock useful for preventing unauthorized persons from emptying the contents of bottles or the like and it may be manufactured inexpensively and efficiently. In many instances a cap of this character is very desirable and, in view of the fact that it may be retailed at a small cost, it may be used in various capacities where a cap of this character would meet a public demand.

Although only one form of the invention has been described and illustrated in detail, it will

be apparent to those skilled in the art that various modifications may be made without departing from the scope of the appended claims.

I claim:

5. 1. A lock for bottle caps or the like comprising an inner shell adapted to be applied to a bottle or the like by turning it, an outer shell covering the inner shell, means retaining the shells assembled but permitting relative rotary movement thereof, and releasable means for locking the shells against such relative rotary movement and comprising a slidable pin extending transversely through a portion of the outer shell and having its end accessible for manual manipulation.
10. 2. A lock for bottle caps or the like comprising an inner cup shape shell adapted to be applied to a bottle or the like by turning it, an outer cup shape shell so covering the inner shell as to provide a space between the base portions of the shells, means retaining the shells assembled but permitting relative rotary movement thereof, separately and relatively rotatable elements in the space, means for locking the shells together when the elements are in predetermined positions, and means accessible to the exterior of the outer shell for separately turning the elements.
15. 3. A lock for bottle caps or the like comprising an inner cup shape shell adapted to be applied to a bottle or the like by turning it, an outer cup shape shell so covering the inner shell as to provide a space between the base portions of the shells, means retaining the shells assembled but permitting relative rotary movement thereof, separately movable and relatively rotatable elements in the space, means jointly on both shells for receiving one of the elements to lock the shells together, and means for preventing movement of the last element into such joint receiving means except when both elements are in predetermined turned positions.
20. 4. A lock for bottle caps or the like comprising an inner cup shape shell adapted to be applied to a bottle or the like by turning it, an outer cup shape shell so covering the inner shell as to provide a space between the base portions of the shells, means retaining the shells assembled but permitting relative rotary movement thereof, a rotary pin extending through the outer shell and such space and being movable in the direction of its length, a pair of cams on the pin and disposed in said space, means locking one cam to the pin for rotary movement therewith, the other cam being free to rotate on the pin, means extending to the exterior of the outer shell for turning the latter cam, means jointly on the shells for receiving one cam when the pin is moved longitudinally, so as to lock the shells together, and means for preventing longitudinal movement of the pin to move the last mentioned cam into locking position, except when the cams are in predetermined, turned positions.
25. 5. A combination lock for bottle caps comprising relatively movable members one of which has a lock receiving space, a rotary pin extending through and to the exterior of the space in one of the members, a pair of cams on the pin and disposed within such space, means securing one of the cams on the pin for rotary movement therewith, the other cam being rotatable relative to the pin, means operatively connected to the last mentioned cam and extending to the exterior of the space for turning said cam on the pin, and means jointly on the members for receiving one of the cams to lock the members together, when the cams are relatively turned to predetermined positions.
30. 6. A combination lock for bottle caps comprising relatively movable members one of which has a lock receiving space, a rotary and transversely movable pin extending through said space and to the exterior of the member, a pair of non-circular cams on the pin, one of which is rotatable thereon, means locking the other cam to the pin for rotation therewith, means connected to the cam which is rotatable on the pin and extending to the exterior of the space, means on one member for preventing transverse movement of the pin and cams except when in predetermined positions, and means for locking the members together when the pin and cams are moved transversely to one position and for releasing the members when the pin and cams are in a different transverse position.
35. 7. A lock for bottle caps or the like comprising an inner shell adapted to be applied to a bottle or the like by turning it, an outer shell covering the inner shell, means retaining the shells assembled but permitting relative rotary movement thereof, and releasable means for locking the shells against such relative rotary movement, said last mentioned means comprising a rotatable pin extending transversely through a portion of the outer shell and which is slidably transversely thereof and rotatable about its own linear axis.
40. 8. A combination lock for bottle caps or the like comprising an inner cup-shaped shell adapted to be releasably secured to a bottle or the like by turning the shell, an outer cup-shaped shell so covering the inner shell as to provide a space between the base portion of the shell, means retaining the shells assembled but permitting relative turning movement thereof, a rotatable and transversely slid able pin extending through the side walls of the outer shell and through such space, a sleeve rotatably mounted on one end of the pin and extending to the exterior of the outer shell so that it may be manually turned from the outside of said shell, a cam in such space and rigidly connected to the inner end of the sleeve, a second cam adjacent the first cam and rigidly connected to the pin, means holding the cams against axial movement on the pin so as to move therewith when the pin is moved transversely through the outer shell, means on the outer shell allowing rotary movement of the pin, sleeve and cams but normally preventing transverse shifting thereof except when the latter cams are in predetermined turned positions, means on the shells for receiving one of the cams when the pin is shifted transversely so as to lock the shells against relative turning movement, and means on the outer end of the pin and sleeve for indicating the turned positions thereof required to so position the cams that the sleeve and pin may be shifted transversely.

BENJAMIN H. ANIBAL.
